CLAIM

The ornamental design for a shoe upper as shown and described.

DESCRIPTION

FIG. 1 is a top, front perspective view of a shoe upper showing my new design.

FIG. 2 is a front elevation view thereof.

FIG. 3 is a rear elevation view thereof.

FIG. 4 is a first side elevation view thereof.

FIG. 5 is a second side elevation view thereof; and,

FIG. 6 is a top plan view thereof.

The broken lines in the Figures illustrate portions of the shoe that form no part of the claimed design.
